EDWARD E. HINRICHSEN, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,262,496.

Specification of Letters Patent.

Patented Apr. 9, 1918.

Application filed August 2, 1916. Serial No. 112,691.

To all whom it may concern:

Be it known that I, EDWARD E. HINRICHSEN, a citizen of the United States, residing at East Orange, in the county of Essex and 5 State of New Jersey, have invented certain new and useful Improvements in Telephone-Exchange Systems, of which the following is a full, clear, concise, and exact description.

10 This invention relates to telephone exchange systems, and more particularly to such systems in which telephone lines of different character terminating at a central office may be indiscriminately interconnect- 15 ed by means of a universal link circuit.

The object of this invention is to provide such a system by means of which the work of the operators is simplified and the time required for completing connections between 20 subscribers is reduced.

In accordance with one feature of this invention there is provided in the usual connecting circuit a listening relay which operates automatically to connect an operator's 25 telephone set with the calling line upon the connection of the link or connecting circuit therewith, and is released to disconnect the operator's telephone set when connection is made with the called line—regardless of the 30 character of the calling and called lines.

This invention will be more fully understood from the following description, reference being had to the accompanying drawings, wherein Figure 1 shows an ordinary 35 cord circuit in which the operator's telephone set is automatically connected to and disconnected from the talking strands and Fig. 2 shows a modification of the scheme shown in Fig. 1.

40 In Fig. 1 there is shown an ordinary common battery subscriber's line A and a magneto subscriber's line B terminating at a central office, at which there is located a universal cord circuit C for interconnecting the subscribers' lines. It will be understood 45 that a large number of subscribers' lines similar to lines A and B may terminate at the central office, but for the sake of simplicity, only the two lines are shown. The universal 50 cord circuit C may be used indiscriminately to interconnect two magnetic lines, two common battery lines or a magneto and a common battery line. Only those portions of the cord circuit C which pertain to the present 55 invention are shown.

The cord circuit C is provided with a differentially wound listening relay 5 having four windings 6, 7, 8 and 9. Winding 6 is connected directly in the answering end 10 of the sleeve strand of the cord circuit in series 60 with the winding of a marginal relay 11, and winding 9 is connected directly in the calling end of the sleeve strand of the cord circuit in series with the winding of a marginal relay 13. The winding 7 is normally 65 short-circuited through the contact of marginal relay 13 and the winding 8 is normally short-circuited through the contact of marginal relay 11. The relays 11 and 13 are of the same resistance. Windings 6 and 9 70 are of the same resistance and number of turns, and windings 7 and 8 are of the same resistance and number of turns. Windings 6 and 7 are connected in series aiding and windings 8 and 9 are connected in series 75 aiding, while windings 6 and 7 are connected in multiple opposing with respect to windings 8 and 9. The resistance of the sleeve conductors of the common battery lines is low, usually about thirty-seven (37) ohms, 80 while the resistance of the sleeve conductors of the magnetic lines is high, usually about two hundred (200) ohms.

If two magneto lines are to be connected together, the insertion of the answering plug 85 20 in the jack of the calling magneto line causes the operation of the listening relay 5 and the cut-off relay over a circuit from battery through the contact of relay 13, winding 6, of relay 5, winding of relay 11, 90 sleeve strand 10, sleeve contacts of the plug 20 and jack of the calling magneto line, and the winding of a cut-off relay (similar to cut-off relay 21 of line B) to ground. Since relay 11 is marginal, it does not operate when 95 in circuit with a high resistance sleeve of a magneto line. The operation of the listening relay 5 connects the operator's telephone set to the talking strands of the cord circuit. Ascertaining that the calling magneto subscriber 100 wishes to be connected with another magneto subscriber, say subscriber B, the operator inserts the calling plug 22 into the jack of B's line, thereupon establishing a circuit for winding 9 of the listening relay 105 5 and the cut-off relay 21 which may be traced from battery through the contact of relay 11, winding 9, winding of marginal relay 13, sleeve strand 12, sleeve contacts of the plug 22 and jack 23 and winding of cut- 110

off relay 21 to ground. Relay 13 is marginal and does not operate. Since the resistance in series with each of the windings 6 and 9 is the same, and since these windings are of 5 the same number of turns and are wound in opposition on the same core, the magnetizing effect of one will be neutralized by that of the other and the armatures of the relay will be released, disconnecting the operator's 10 telephone set from the talking strands.

If two common battery lines are to be connected together, the insertion of the answering plug 20 into the jack 25 of line A will cause the operation of the listening relay 5, 15 marginal relay 11 and cut-off relay 26 over a circuit from battery through the contact of relay 13, winding 6, winding of relay 11, sleeve strand 10, sleeve contacts of plug 20 and jack 25 and winding of cut-off relay 20 26 to ground. The operation of marginal relay 11 removes the short circuit from winding 8, so that when the calling plug is inserted into the jack of another common battery line, marginal relay 13 and the cut- 25 off relay of the line will be operated over a circuit from battery through windings 8 and 9 of relay 5, winding of relay 13, sleeve strand 12, sleeve contacts of plug 22 and jack of the called common battery line and 30 winding of cut-off relay thereof to ground. The operation of marginal relay 13 removes the short circuit of winding 7 so that the magnetizing effect of windings 8 and 9 will be neutralized by that of windings 6 35 and 7, permitting the listening relay to release its armatures.

Should it be desired to connect a magneto line with a common battery line, the insertion of the answering plug 20 into the jack 40 of the magneto line causes the operation of the listening relay 5, but not the operation of the marginal relay 11, as before explained. Insertion of the calling plug 22 into the jack of the common battery line 45 causes the operation of the marginal relay 13 which removes the short circuit from the winding 7. Windings 6 and 7 in series are now opposed to winding 9, but due to the high resistance of the sleeve of the magneto line in series with windings 6 and 7, the amount of current through these two windings is less than that through winding 9, which is in series with the low resistance sleeve of the common battery line. However, 55 the number of turns in winding 7 is so proportioned that under the conditions mentioned, the number of effective ampere turns of windings 6 and 7 will be equal to that of winding 9, so that the relay 5 will 60 release its armatures.

If a common battery line is to be connected to with a magneto line, the number of effective ampere turns for the differential listening relay 5 will be equalized in a manner similar to that just described, except 65

that the short circuit will be removed from winding 8 instead of winding 7.

In the cord circuit shown in Fig. 2, a differential listening relay 5' is provided with windings 6', 7', 8', 9', similar to the windings of the relay 5 shown in Fig. 1. In the relay 5', however, the windings 6' and 7' are normally in series, and 8' and 9' are normally in series. A marginal relay 11' controls the short-circuiting of winding 7', 75 while a marginal relay 13' controls the short-circuiting of the winding 8'. It is believed that the operation and coöperation of these three relays will be thoroughly understood without any further discussion. 80

What is claimed is:

1. A telephone exchange system comprising a plurality of common battery and local battery telephone lines, the common battery lines having sleeve resistances differing in value from that of the local battery lines, a link circuit for interconnecting the lines indiscriminately, an operator's telephone set, a differential relay having a winding associated with each end of a strand of the link circuit and operating when one end of the link circuit is connected with either a common battery or local battery line to connect the operator's telephone set with the line, and means coöperating in one manner with the sleeve resistance of a common battery line and in a different manner with the sleeve resistance of a local battery line when the other end of the link circuit is connected therewith to cause the equalization of the ampere turns of the windings of the differential relay, thereby causing the release thereof to disconnect the operator's telephone set from the line. 95

2. A telephone exchange system comprising a plurality of common battery and local battery telephone lines, the common battery lines having sleeve resistances differing in value from that of the local battery lines, a link circuit for interconnecting the lines 105 indiscriminately, an operator's telephone set, a differential relay having a winding associated with each end of a strand of the link circuit and operating when one end of the link circuit is connected with either a common battery or local battery line to connect the operator's telephone set with the line, and a relay coöperating in one manner with the sleeve resistance of a common battery line and in a different manner with the 110 sleeve resistance of a local battery line when the other end of the link circuit is connected therewith to cause the equalization of the ampere turns of the windings of the differential relay, thereby causing the release 115 thereof to disconnect the operator's telephone set from the line. 120

3. A telephone exchange system comprising a plurality of common battery and local battery telephone lines, a link circuit for in- 130

- terconnecting the lines indiscriminately, an operator's telephone set, a differential listening relay energized upon connection of one end of the link circuit with either a common battery or a local battery line to connect the telephone set with the line and deenergized upon connection of the other end of the link circuit with either a common battery or a local battery line to disconnect the telephone set from the line, a plurality of windings for the listening relay, and means associated with each end of the link circuit and controlled by the connected lines for determining the number of windings effective for controlling the operation of the listening relay.
4. A telephone exchange system comprising a plurality of common battery and local battery telephone lines, a link circuit for interconnecting the lines indiscriminately, an operator's telephone set, a differential listening relay energized upon connection of one end of the link circuit with either a common battery or a local battery line to connect the telephone set with the line and deenergized upon connection of the other end of the link circuit with either a common battery or a local battery line to disconnect the telephone set from the line, a plurality of windings for the listening relay, and means associated with each end of the link circuit and controlled by the connected lines for determining the number of windings effective for controlling the operation of the listening relay.
5. A telephone exchange system comprising a plurality of common battery and local battery telephone lines, a link circuit for interconnecting the lines indiscriminately, an operator's telephone set, a differential listening relay energized upon connection of one end of the link circuit with either a common battery or a local battery line to connect the telephone set with the line and deenergized upon connection of the other end of the link circuit with either a common battery or a local battery line to disconnect the telephone set from the line, a plurality of windings for the listening relay, and means associated with each end of the link circuit and controlled by the connected lines for determining the number of windings effective for controlling the operation of the listening relay.
6. A telephone exchange system comprising a plurality of common battery and local battery telephone lines, a line signal and a controlling cut-off relay for each line, the resistance of the common battery cut-off relay being different from that of the local battery cut-off relay, a link circuit for interconnecting the lines indiscriminately, an operator's telephone set, an energizing circuit for the differential relay established upon the connection of one end of the link circuits with a line of either character and including the winding of the cut-off relay of the engaged line and one winding of the differential relay, a deenergizing circuit for the differential relay established upon the connection of the other end of the link circuit with a line of either character and including the winding of the cut-off relay of the engaged line and the other winding of the differential relay, and means governed by and coöperating with the cut-off relay of the engaged lines for equalizing the ampere turns of the windings of the differential relay.
7. A telephone exchange system comprising a plurality of telephone lines of different character, a universal link circuit for interconnecting the lines, an operator's telephone set, a differential relay having a plurality of windings and energized upon connection of one end of the link circuit with a line of either character to connect the operator's telephone set with the line, and deenergized upon connection of the other end of the link circuit with a line of either character to disconnect the operator's telephone set, and a relay in each end of the link circuit and operating when connection is made with a line of one character and not operating when connection is made with a line of another character to determine the number of the windings effective for energizing and deenergizing the differential relay.

In witness whereof, I hereunto subscribe my name this 31st day of July, A. D. 1916.

EDWARD E. HINRICHSEN.
